UNITED STATES PATENT OFFICE.

EDWARD B. HESS, OF MANHATTAN BEACH, NEW YORK, ASSIGNOR TO ROYAL TYPE-WRITER COMPANY, INC., OF NEW YORK, N. Y., A CORPORATION OF NEW YORK.

TYPEWRITING MACHINE.

Application filed November 12, 1921. Serial No. 514,756.

To all whom it may concern:

Be it known that I, EDWARD B. Hess, a citizen of the United States, residing at Manhattan Beach, in the county of Kings,

5 New York, and State of New York, have invented certain new and useful Improvements in Typewriting Machines, of which the following is a specification.

This invention relates to typewriting machines of the front strike visible kind and particularly to type actions of the kind shown in my Patent No. 1,390,708, of September 13, 1921, in which provision is made for reducing the noise made by the impact 10 of the type on the platen. This is accomplished as described in said patent, by causing each type bar to be moved, by the depression of a key, to a point considerably in advance of the platen, the further movement of the type bar to the platen being caused by the momentum of the type bar. The mechanism shown in said patent is such that when a key is depressed to its full extent the associated type bar is carried to a 15 predetermined point in front of the platen when the momentum period begins, at which time certain members of the action are in a dead-center or toggle-locking position. During this momentum period, after the 20 dead-center position is passed, the depressed key has a short return or upward movement which is resisted by the finger of the operator. On the return of the type bar the key lever is raised to normal position.

25 According to my present invention I so modify the mechanism that while the type bars are properly brought to the momentum period by the depression of the keys, the short return movement of the keys during the momentum period is avoided, certain members of the action being extended to permit the type bars to proceed to the platen after the dead-center position of parts of the mechanism has been reached. In this 30 way the key levers are cushioned and a very light and delicate touch is afforded.

The escapement mechanism is operated during the latter part of the movement of the type bars by improved mechanism 35 whereby double printing is avoided, and the speed of operation is increased. One way of embodying my improvements is shown in the accompanying drawings, in which,

40 Figure 1 is a view, partly in section and partly in side elevation, of parts of a type-

writing machine with my improvements applied, only such parts of the mechanism being shown as are necessary to illustrate my improvements;

Figure 2 is a detail view showing parts 60 of the devices for operating the escapement, the parts shown being in the position which they assume when the type bar has reached the printing point and the escapement operated.

A portion of a typewriter carriage is indicated at A, and B indicates a platen. C indicates a type bar segment and D a type bar guide. E indicates part of the ribbon vibrator devices. Escapement mechanism is 70 indicated at F. G indicates a key lever and H a type bar. The segment is, as usual, semi-circular and the type bars are pivotally connected therewith at e, while the outer ends of the type bars are normally 75 supported in a cushioned type bar rest I. The key levers are pivotally mounted in a frame J at g, and their upward movement is limited by a cushioned stop K. Front links or levers N are pivotally connected 80 with a frame M, and these links or levers are link-connected as shown at n with the key levers G. The heels of the type bars are connected with the rear ends of the levers N by link members O. These members are connected at o to the levers N and at o' to the heels of the type bars. Each member O comprises a closed closely wound coiled spring o², the opposite ends of which are connected with short rods o³. The parts 85 are so adjusted that normally when the key levers are in normal position the members occupy the position shown in Fig. 1. When a key lever is depressed the parts are moved to the position shown by the line x in Fig. 90 1. This is done without stretching or extending the member O and at that time the pivot points o, o' and e are in a straight line with each other—that is, in a dead-center or toggle-locking position and the 95 type bar reaches the position H' which is a considerable distance from the platen. The key lever can, however, be further depressed by the operator, but in doing so the spring o² is extended, stretched or lengthened and at the same time the type bar is carried by its momentum to the dotted line position H² in Fig. 1. This also stretches the spring o². It will thus be seen that the spring o² not only permits the type bar to pass to the print-

ing point from its position H' , but it also permits the key lever to be further depressed if the operator so desires. In this way the key is cushioned, which is a desirable feature in typewriting machines.

The expression extensible member or member of variable length is used to designate a form of connection in which the actual length of the member is varied or in which 10 the distance between the ends of the member measured along the member itself is changed. It is obvious that it may be a single unitary member, or one consisting of a plurality of parts so long as this condition is fulfilled.

Return springs y for the key levers are attached to their projections G' and at their opposite ends to a collective adjustment plate G^2 .

20 A universal bar is mounted below and in rear of the heels of the type bars. This universal bar consists of a rock-shaft R , mounted in brackets T , which may be supported on the main frame of the machine.

25 The rock-shaft R carries arms r , which are connected at their front ends by a rod S . Links P are connected to the heels of the type bars and have looped ends p' , through which the rod S extends. Each link P is 30 surrounded by a coiled spring p , which is attached to a plate Q , carried by arms q depending loosely from the rock-shaft R . U indicates one of the cam disks which engages an arm q by means of which said arm q and the plate Q may have their position 35 changed to vary the tension of the springs p , all of which are connected to said plate Q and may thus be collectively adjusted.

The arms r engage the cam disks U when 40 moved downwardly, and thus their downward movement is limited. As shown, when the type bars are at rest the closed ends of the links P do not operatively engage the rod S . When the type bars are raised to 45 the position H' in Fig. 1, the lower rear closed ends of the links come in contact with the rod S . When the type bars move to the printing point the links, being operatively engaged with the rod S , cause the 50 universal bar to be rocked.

The rock-shaft R carries an arm V which operates the escapement. This arm, near its upper end, is connected with a spring v , the front end of which is connected with a 55 plate v' , depending from the segment C . This spring normally holds the upper end of the arm V away from the escapement mechanism and also holds the arms r and the rod S in lower position. The escapement 60 mechanism is in general similar to that usually employed on the Royal typewriting machine. The rack bar is indicated at W . W' indicates an escapement wheel and W^2 a pinion engaging the rack bar. F' indicates 65 a roller dog carried by the rocker plate f

and F^2 indicates a limber or spacing dog. The rocker plate is pivotally connected with the escapement frame at f^3 and a spring f^0 connected with the rocker plate and with the frame F^3 normally holds the rocker plate 70 and the fixed dog in the position shown in Fig. 1. The rearward movement of the upper part of the rocker plate is limited by an adjustment screw f^4 . The rocker plate carries a roller carrying spring arm f' , the position 75 of which may be adjusted by screw f^2 . The devices are so organized that normally the fixed roller carrying dog F' engages the escapement wheel and when the escapement mechanism is operated by the universal bar 80 the fixed dog leaves the escapement wheel and the limber dog is brought into engagement therewith, quickly turns on its pivot and the carriage advances one space. In this way I provide what is known as a reverse or speed escapement. Inasmuch as the escapement is operated during the latter part of the movement of the type bars the danger of double printing is avoided and the speed of operation is increased as the 85 carriage is quickly released as soon as the fixed dog is disengaged from the escapement wheel, the distance moved by the carriage being determined by the limber dog.

f^7 is a limiting stop to prevent overthrow 90 of the escapement rocker plate. This invention is not limited to the use of a reverse or speed device, as the escapement mechanism usually employed in Royal typewriting machines give an acceptable result. 100

I claim as my invention:

1. In a typewriting machine the combination with a key lever and a type bar of connections therebetween, including a member of variable length, for moving the type bar, by the full operative depression of the key, to a predetermined position in front of the platen, the further movement of the type bar to the platen being caused by the momentum thereof, during which movement the key may receive a further depression due to the variation in length of said member.

2. In a typewriting machine the combination with a key lever and a type bar of 115 connections therebetween, including a member of variable length, for moving the type bar, by the depression of the key, to a predetermined position in front of the platen, the further movement of the type bar to 120 the platen being caused by the momentum thereof during which momentum period the length of said member is increased.

3. In a typewriting machine the combination with a key lever and a type bar of 125 toggle link connections therebetween, including a member of variable length, for moving the type bar, by the depression of the key to a predetermined position in front of the platen, the further movement of the 130

- type bar to the platen being caused by the momentum thereof, during which momentum period the length of said member is increased.
5. 4. In a typewriting machine the combination with a key lever and a type bar, of link connections therebetween, including a member of variable length, for moving the type bar, by the depression of the key to a predetermined position in front of the platen and at a considerable distance therefrom, the further movement of the type bar to the platen being caused by the momentum thereof, during which momentum period the links are brought past a dead center position and the length of said member is varied.
5. In a typewriting machine the combination with a key lever and a type bar of connections therebetween, comprising a link mounted to move about a fixed axis and which is link-connected to the key lever, and an extensible link connecting said first-mentioned link to the heel of the type bar, said connections being operated by the depression of the key to move the type bar to a predetermined position considerably in advance of the platen, the further movement of the type bar to the platen being caused by the momentum thereof during which momentum period the extensible member is stretched.
6. In a typewriting machine the combination with a key lever and a type bar of connections therebetween, including a member of variable length, for moving the type bar, by the depression of the key, to a predetermined position considerably more than 5° in front of the platen, the further movement of the type bar to the platen being caused by the momentum thereof during which momentum period the length of said member is increased and the key lever may be further depressed.
45. 7. In a typewriting machine the combination with a key lever and a type bar of connections therebetween, including an extensible link connected with the heel of the type bar in substantially the same vertical plane with the pivot of the type bar, said link being connected with the key lever and being moved by the depression of the key sufficiently to carry the type bar to a position considerably in advance of the platen, the further movement of the type bar to the platen being caused by the momentum thereof during which momentum period the extensible link is stretched.
8. In a typewriting machine the combination with the pivoted type bar and the key lever for operating them, of an escapement, a universal bar comprising a rock shaft, a vertically arranged arm for operating the escapement, a horizontally arranged rod supported on the rock shaft, a spring for holding the arm in normal position, a link connected with the type bar and having a lost motion connection with the rod, a spring connected with the heel of the type bar for returning it to normal position, and means for adjusting the tension of said springs.
9. In a typewriting machine the combination with a key lever and a type bar of connections therebetween, including a link formed as a single unitary extensible member, for moving the type bar, by the depression of the key, to a predetermined position in front of the platen, the further movement of the type bar to the platen being caused by the momentum thereof during which momentum period the extensible member is stretched.
10. In a typewriting machine the combination with a key lever and a type bar of connections therebetween including a link comprising a closely coiled spring, for moving the type bar, by the depression of the key, to a predetermined position in front of the platen, the further movement of the type bar to the platen being caused by the momentum thereof during which momentum period the coiled spring is stretched.

In testimony whereof, I have hereunto subscribed my name.

EDWARD B. HESS.
